PHOTOGRAPHIC PRINTING DEVICE

Filed March 17, 1927

Inventor:

William T. Foster
Monroe Miller

Attorney.

UNITED STATES PATENT OFFICE.

WILLIAM T. FOSTER, OF EASTON, PENNSYLVANIA, ASSIGNOR TO FISHER SCIENTIFIC COMPANY, OF PITTSBURGH, PENNSYLVANIA, A CORPORATION OF PENNSYLVANIA.

PHOTOGRAPHIC-PRINTING DEVICE.

Application filed March 17, 1927. Serial No. 176,190.

The present invention relates to photographic printing appliances, and aims to provide a novel and improved photographic printing device adapted especially for making photographic reproductions of bacterial colonies growing in culture mediums in Petri dishes, such as disclosed in my copending application Serial No. 176,191 filed even date herewith, although the device may be 10 used for making other photographic prints.

Another object of the invention is the provision of such a device embodying a holder for the sensitized card or sheet and Petri dish or other plate or sheet used as a negative, an electric lamp and means for concentrating the light rays on the Petri dish or negative.

A further object is the provision of such a device having printing and red electric lamps 20 mounted in a novel manner so that either lamp may be conveniently removed, and the lamps used in various arrangements.

A still further object of the invention is the provision of a photographic printing device 25 comprising a novel and convenient assembly of the component elements.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

35 The invention is illustrated in the accompanying drawing, wherein—

Figure 1 is a front elevation of the improved printing device.

Fig. 2 is a vertical section thereof on the 40 line 2—2 of Fig. 1.

Fig. 3 is a plan view of the holder for the sensitized card or sheet and the Petri dish or negative.

A rectangular upright frame 7 is provided 45 which is open at the front and also at the rear, although it may be closed at the rear if desired.

The holder for the sensitized card or sheet and Petri dish or plate is disposed slidably 50 on the bottom of the frame 7, and comprises a rectangular tray 8 slidable between the sides of the frame on the bottom thereof under cleats 9 carried by the sides of the frame to hold the tray on the bottom of said frame.

The card or sheet 10, which may be of the kind disclosed in said application Serial No. 176,191, is placed within the tray on the bottom thereof with its sensitized surface uppermost, and the Petri dish or plate 11 is placed in the tray over the card 10 and contains a film of culture medium thereon in which are grown the bacterial colonies 12 of a sample of milk, water or other material used in bacteriological investigation, although it will be understood that if the present device is used for other photographic printing purposes, the Petri dish 11 may be substituted by the usual negative. A cover 13, which serves as a light shield also, is disposed within the tray, and is hinged, as at 14, 70 to the rim of the tray to swing upwardly for placing the card 10 and Petri dish 11 in and removing them from the tray. The cover 13 has a finger hold 15 which may be used for conveniently swinging said cover open, 75 and the cover has an opening 16 through which the light may pass, said opening being of a size to provide the desired field on the card 11 when the print is made. The tray may be readily slid from the frame 9 for placing the card 10 and Petri dish 11 in and removing them from the tray.

The light for printing is furnished by an electric lamp 17 which is engaged within and suspended from a lamp socket 18 secured to the lower surface of a slide 19 disposed slidably between the sides of the frame or cabinet 7. The sides of the frame have plates 20 between which the slide 19 is movable, and said slide may be readily slid forwardly out of 90 the frame.

In order to concentrate the light rays on the Petri dish 11 and card 10 through the opening 16, a cylinder 21 surrounds the lamp 17 and is suspended from hangers 22 secured to the lower surface of the slide 19. The upper and lower ends of the cylinder are open, and are spaced from the slide 19 and tray 8, respectively, for the upward flow of air through the cylinder to keep same cool and thereby avoid overheating, especially such as might be injurious to the bacterial growths on the Petri dish 11. The cylinder 21 is located immediately above the opening 16 of the tray cover 13 so that the light rays from the lamp 17 are concentrated to the area bounded by the edge of the opening 16.

A double switch 23 of any suitable kind

is carried by one side of the frame 7 at the exterior of the frame, and wires 24 extend from the socket 18 to the switch 23, for connection with a source of electrical current (not shown), and the switch 23 may be conveniently operated for lighting and extinguishing the lamp 17.

A small electric lamp 25 with a red bulb is disposed above the slide 19, being secured 10 within and suspended from a lamp socket 26 secured to the lower surface of an upper slide 27 that is movable under the top of the frame 7 in guide cleats 28 secured to said top of the frame. Flexible wires 29 connect the socket 26 with the switch 23 so that the lamp 25 may be lighted and extinguished, the switch 23 being a double switch in order that each lamp 15 may be controlled independently of the other lamp.

20 The electric lamps may be readily replaced by removing the slides 19 and 27 from the frame 7, and the printing lamp 17 may be of various candle powers. The removal of the slides containing the lamps is also of advantage for other purposes. Thus, the lamp 25 may be removed with the slide 27, and by inverting the lamp and slide the same may be seated on top of the frame 7 or at any other suitable point for convenience in placing the 25 card 10 and Petri dish 11 in or removing them from the tray when the tray has been removed from the frame. Likewise, the lamp 17 may be removed from the frame with the slide 19. The wires 24 and 29 are sufficiently long to permit the slides to be removed 30 from the frame and seated on the surface on which the frame 7 rests. It will also be noted that when the slide 19 is removed from the frame 7, with the slide 27 in place, the lamp 25 will enable the tray to be positioned properly in the frame, said tray being illuminated by red light from above. Then, when the slide 19 is placed back in the frame it obstructs the light from the lamp 25, although 35 the light from said lamp may pass out from between the slide 19 and top of the frame. The lamp 17 is then lighted for the required period and time to complete the printing, after which the lamp 17 is extinguished and the tray 8 removed.

40 In order to provide for uniform light intensity within the opening 16, the bulb of the lamp 17 may be frosted or otherwise treated so as to diffuse the light rays, or a frosted 45 glass or other light diffuser 30 may be provided in the cylinder 21 below the lamp 17.

Having thus described the invention, what is claimed as new is:—

1. An apparatus for making photographic prints directly from an analytical specimen 60 comprising a frame, an electric lamp mounted in said frame, a printing tray slidably disposed in said frame, and light concentrating means surrounding said lamp and projecting toward said tray, said tray having a sensitized-paper receiving base portion and a removably attached cover adapted to receive and hold a specimen in printing relation to the paper.

2. An apparatus for making photographic 70 prints comprising a frame, an electric lamp mounted in said frame, a printing tray slidably disposed in said frame, and provided with a hinged cover having a specimen receiving opening therethrough, and a light-concentrating cylinder open at both ends disposed about said lamp and directed toward said opening.

3. A device of the character described comprising a frame, a removable holder therein, 80 a removable slide in the frame, an electric lamp carried by said slide, and means carried by said slide within and spaced from the frame and surrounding said lamp and projecting toward said holder to concentrate the 85 light rays on an area of said holder.

4. A device of the character described comprising a frame, a removable holder therein, a removable slide in the frame, an electric lamp carried by said slide, and a cylinder 90 carried by said slide surrounding said lamp and having both ends open, said cylinder being arranged to concentrate the light rays on an area of said holder.

5. A device of the character described comprising a frame, a holder mounted in the frame, a red electric lamp mounted in said frame, a slide mounted removably in the frame between said holder and lamp, and a printing electric lamp carried by said slide 100 between said slide and holder.

6. A device of the character described comprising a frame, a holder therein, a removable slide in the frame, a red electric lamp carried by said slide, a second removable 105 slide in the frame between said lamp and holder, and a printing electric lamp carried by the second slide between said second slide and holder.

In testimony whereof I hereunto affix my 110 signature.

WILLIAM T. FOSTER.
